CERAMIC CASTING APPARATUS

Robert R. Salmans, Wichita, Kans., assignor to Ceramics
of Kansas, Inc., Wichita, Kans., a corporation of Kansas

Filed May 13, 1968, Ser. No. 11,891

Term of patent 14 years

Int. Cl. D15—05

U.S. Cl. D55—1

FIG. 1

FIG. 2

FIG. 3

FIGURE 1 is a side view of ceramic casting apparatus showing my new design.

FIGURE 2 is a view of the opposite side thereof.

FIGURE 3 is a top view thereof.

FIGURE 4 is a bottom view thereof.

FIGURE 5 is an end view thereof.

FIGURE 6 is a view of the opposite end thereof.

FIGURE 7 is a view thereof of partly longitudinal sectional nature to more clearly show in full lines the visible, upwardly open cavities and showing the outline thereof in profile for convenience of illustration.

FIGURE 8 is a view thereof like FIGURE 7 except being of transverse sectional nature taken generally on line 8-8 of FIGURE 7 and showing the outline thereof in profile for convenience of illustration.

I claim:

The ornamental design for a ceramic casting apparatus, as shown and described.
